TELEGRAPH SYSTEM

Henri Chireix, Paris, France, assignor to Compagnie Generale de Telegraphic Sans Fil, a corporation of France

Application December 26, 1946, Serial No. 718,510
In France November 16, 1939

Section 1, Public Law 690, August 8, 1946.
Patent expires November 16, 1959.

4 Claims. (Cl. 178—2)

1

In the Morse system, Baudot system and the like it is known to define as a time unit, or telegraphic time the duration of the shortest signal. The letters, or signals, are then formed by a certain number of signals which as such correspond with a certain number of telegraphic times and which succeed one another in a certain number of telegraphic times. Thus, in the Morse code generally employed a dot corresponds with one telegraphic time, a dash corresponds with three telegraphic times and likewise an interval between letters corresponds with three telegraphic times and an interval between words to five telegraphic times. In the Baudot code a letter is always characterized by 10 telegraphic times and the emissions correspond with one, or several dots of a duration equal to one telegraphic time period. The origin of one telegraphic time period can then be marked by a transitory rule residing in the application, or cessation of a signal, or by no occurrence at all if the code employed demands that at this instant nothing should take place.

In accordance with the present invention, for the transmission of intelligence, means are provided for sending of brief current impulses which are transmitted along the line (by the station antenna in case of radio transmissions) ahead of the telegraphic times and of same sense and only at the beginning of those characterized precisely by the absence, in the code employed, of variations of the system (for instance, in the Morse code at the beginning of the second and third telegraphic times corresponding with a mark or a dash, or with a space or an interval between letters). Means are provided for codifying the intelligence to be transmitted in accordance with dots, dashes and spaces which are commensurate with the elemental signal periods and odd multiples thereof.

These brief current impulses received at the end of the line (or at the station receiver output in the case of transmission by radio) will have as their effect the blocking of synchronous locally derived periodic electrical impulses which are delivered during alternate ones of a succession of elemental signalling periods. The locally derived impulses are likewise of brief duration and emitted at the beginning of the telegraphic times, but being shiftable by said impulses alternately positive and negative and actuating a relay to a condition of spacing significance and a condition of marking significance. A relay operating under such conditions has long been known in telegraphy (Gulstad relay).

Under these conditions it is seen that at the beginning of the telegraphic times characterized,

2

in the code employed, by a change in the system, the receiving relay will see-saw in view of the fact that no impulse will stop it, while on the contrary the short impulses, transmitted while no change in the system occurs in the code transmitted, will block the receiving relay in the position primitively attained. The imprinter controlled by the receiving relay thus will reproduce the code of the starting.

10 The advantages of the system, whose above exposition describes the principle, are principally evidenced in the case of radio transmissions on short waves and can be briefly summarized as follows:

15 1. The emission requiring but a small fraction of the total time, there is realized an important saving in the consumed power and the instantaneous power can be generally increased to a definite extent.

20 2. The system is secret up to a certain point.

3. The mutilation of the signals owing to fading effects and to echo effects is largely eliminated owing to the fact that only the wave having followed the shortest path releases the receiving operation.

25 A particularly simple embodiment of the invention to which the latter is not limited, however, will now be described by way of example.

In the drawing Figure 1 represents a portion of the transmitter circuit,

30 Fig. 2 represents a portion of the receiver circuit,

Fig. 3 is a graphic diagram of the relay receiving telegraphic periods in the absence of receiving impulses,

35 Fig. 4 is a graphic diagram of the relay when a dash has been received equal to three times the telegraphic period with the relay contacts dwelling in a position *a*,

40 Fig. 5 is a graphic diagram of the relay when a dash has been received equal to three times a telegraphic period with relay contacts dwelling in a position *b*,

Fig. 6 illustrates a part of the Morse code significant of the letters *i am*,

45 Fig. 7 represents the transmission of the letters *i am* of Fig. 6, and

Fig. 8 represents the relay movement for the letters *i am*.

50 There is a two position contact number indicated by *1* in Fig. 1 which is a form of an impulse type transmitter controlled by a perforated tape. Such transmitter closes the contacts *a*, or *b* only at the moment in which the pecker-pins enter the perforations of the tape, i. e., during a rather small fraction of the telegraphic times.

55 The embodiment herein described will be un-

derstood by those skilled in the art to be best adapted to a system in which the transmitting tape has two rows of perforations; those in one row defining the front edge of a marking signal, and those in the other row defining the front edge of a spacing signal. The two pecker-pins which are aligned with the two rows of perforations control the contact member 27 in such manner that contacts *a* are closed at the commencement of a marking signal, and contacts *b* are closed at the commencement of a spacing signal. A tape perforation in one row is, therefore, always followed by a tape perforation in the other row. But these perforations are spaced apart in accordance with the occurrence of dots, dashes and spaces of different duration.

A distributor switch 2 is driven in synchronism with contacts 1 and closes the voltage source 3 at each telegraphic time during a time which is shorter than that during which the contacts *a*, or *b* are established. By means of the brush 25 the contacts of the distributor 2 can be closed during a portion of the contacting times at *a* and *b*. The voltage source 3 feeds across the resistances 4 and 5, the screen grid of a multi-electrode tube 6 whose control grid is fed with tone frequency through the transformer 7 and is suitably biased by the direct current source 8.

The plate is connected to an output transformer 9 and to a voltage source 10 which may, in fact, be the same source as 3.

The operating mode will be readily understood. In the absence of perforations in the tape, i. e., since at the beginning of the telegraphic times no change occurs in the system according to the code employed, a positive potential is applied by the distributor 2 to the terminals of the bias resistance 5 connected to the screen of the tube 6 (herein shown as a pentode). There appears then at the terminals of the secondary of the transformer 9 a potential impulse of tone frequency.

However, at the moment where there occur perforations in the band, the contacts then established in *a*, or in *b*, short circuit the resistance 5. The current impulses traversing the distributor and whose value is limited by the resistance 4, no longer can unblock the tube 6. Thus no impulse manifests itself at the output of the transformer 9. The previously enunciated conditions are thus realized.

The transformer 9 can be connected to the transmission line, or can act upon a radio transmitter.

In Fig. 2 showing the receiving end, a transformer 11 is represented which receives the audible impulses furnished by the transmission line (eventually after amplification, limitation, filtering, etc.) or furnished by the radio receiver.

These impulses are detected in the tube 12, which operates as a grid cut-off or limiter tube. To this end, tube 12 is biased by the source 13 so as to permit plate current to flow only at peaks of the control impulses. The grid circuit of said tube contains a resistance 14 having a very high value so as to limit the amplitude at the appearance of grid current. The anode of the tube 12 is connected across a resistance 15 to the direct current source 16. Capacitor 17 in shunt with resistor 15 provides a filtering action. Variations in the anode potential of the tube 12 are transmitted across a variable resistor 18 to the distributor switch 19 which rotates in synchronism with the distributor 2 of Fig. 1. This distributor also establishes a contact at each tele-

graphic time, but alternatively on one of the two diametrically opposite brushes *a*, *b*, which are mounted on one support so as to be phase-adjusted as a unit.

These brushes are connected to two identical resistances 20, whose common point is connected to ground across the direct negative biasing source 21. The brushes are connected also to the grids of two triodes 22, whose anodes are connected to the battery 23 across the coils of a polarized relay 24. The relay contacts 26 control the printer, or translator.

The operating mode is likewise easily understandable. In the absence of impulses coming from the line, the current of the tube 12 is zero and the anode of this tube is at the potential of the source 16. Under these conditions, when the sectors of distributor 19 move in front of the brushes, a current taking the path 16, 15, 18, 19, 20 and 21 establishes itself. The potential drop at the terminals of 20 opens successively the one and the other one of the two tubes 22, and the relay 24 see-saws alternatively from one position to the other one. When an impulse manifests itself in 11, the potential of the anode 12 drops to a much lower value and the grids of the tubes 22 are no longer free. The relay 24 thus remains in the previous position. The position of the brushes *a* and *b* is obviously controlled in a manner such that the contacts are established in *a* and *b*, at the moment in which the impulses can be produced. Hence, also the previously enunciated conditions are realized.

The mode of operation of receiving telegraphic code will now be described in greater detail with reference to Figs. 3 to 8 inclusive of the drawings.

Because of the rotation of the ticker 19 shown in Fig. 2, the relay 24 alternately shifts the contact reed from one position to make contact with a fixed contact 26a to the other fixed contact 26b in time sequence with the telegraphic work period. This contact reed movement is prolonged as long as the primary of the transformer 11 does not receive impulses. Fig. 3 shows the time periods number 1, 2, 3, 4, 5, etc. each period corresponding to a telegraphic period and shown by the abscissae plotted against the amplitudes of the reed of relay 24 indicated by the ordinates and which are assumed to correspond in upward direction to the making of contact 26a and in downward direction to the making of contact 26b. In the example that has been chosen contact 26a is closed at the beginning of each odd telegraphic period or odd multiples thereof, whereas the contact 26b is closed at the beginning of each even telegraphic period.

Let us now suppose, as is indicated by Fig. 4, that an impulse of brief duration in comparison with the telegraphic period or rate has been fed into the transformer 11 at the beginning of such period 8. As outlined above the relay 24 which at this instant would rock toward the contact position 26b stays in the contact position 26a because of the non-block (or cutoff) condition of tube 22 corresponding thereto. At the beginning of the telegraphing period 9 the relay 24 which is in position 26a stays therein; in fact, this is the situation regardless of whether at that instant an impulse reaches the transformer 11 or not. In short, the arrival of an impulse at the beginning of period 8 has the result of replacing the portion of cdefghij shown by Fig. 3 for the portion indicated by Fig. 4 as cdij, in other words, to cause the appearance of a dash di having a length equalling three times

the telegraphic period. In the same way the arrival at the transformer 11 of an impulse at the beginning of telegraphic period 13, for instance, as shown by Fig. 5 there results in the appearance of a "blank space" k1 the length of which amounts to three times the telegraphic period, the same extending from the beginning of the time sequence 12 to the end of the telegraphic period 14. The arrival of an impulse at the beginning of the telegraphic period 14 would remain ineffective as regards movement of relay 24 for the same reasons as hereinbefore indicated. But if an impulse does come in at the beginning of period 15 it would extend to m, that is to say, to two telegraphic periods, the "blank" k1.

In a practical application of the method outlined above suppose that the words "I am" are intended to be transmitted in Morse code as shown by Fig. 6. Fig. 7 represents the impulses (assumed to be infinitely brief for the sake of simplifying the illustration) required to transmit the "blank" or space five telegraphic period separating the words I and am, the "dash" of letter "a," the two dashes of letter "m" and the blank of three times the telegraphic period separating the latters "a" and "m."

Fig. 8 represents the movement of relay 24 by action of the above mentioned impulses.

It will be noted that the single dot representative of the letter "I" coincide with the "dashes" that precede, corresponding to the rocking or shifting motion of the reed of relay 24 in the absence of impulses. Similarly the letter "m" may as one wishes be taken for a letter "g," for a "z" or for a numeral "7." In order to avoid these inconveniences all that is necessary is to provide in actual operation the sending of the conventional signals at the beginning and the end of a message. If the series of impulses as shown by Fig. 7 is shifted an odd number of telegraphic periods in the right-hand or left-hand direction, the "dashes" Fig. 8 become the "blanks" and vice versa. However, no confusion is liable to be caused, for the fact that five telegraphic periods could be nothing else but spaces or blanks. It would also be feasible to provide for the conventional beginning and end signals of a message a dash (or a blank) amounting to 9 telegraphic periods, that is to say, a sequence of four impulses spaced two periods apart. One would thus be able immediately to receive the portion (either the upper or the lower) of Fig. 8 corresponding to the "dashes."

I claim:

1. A system for the transmission of intelligence comprising a receiver having means normally responsive to locally derived periodic electrical impulses, said impulses being delivered during alternate ones of a succession of elemental signalling periods, said means being shiftable by said impulses to a condition of marking significance and being shiftable during intermediate periods to a condition of spacing significance, a transmitter having means for sending to said receiver signals each element of which is limited in duration to a discrete one of said elemental signalling periods, means for codifying the intelligence to be transmitted in accordance with dots, dashes and spaces which are commensurate with said elemental signalling periods and odd multiples thereof, and means at the receiver for combining the effects of the locally derived impulses and the transmitted impulses in such manner

that the responsive means is caused to follow and to signify the dots, dashes and spaces of the codified intelligence.

2. A telegraph system for transmitting brief marking impulses spaced apart by integral multiples of an elemental period, comprising at one location a two-position contact member, having a pair of contacts oppositely disposed with respect to an arm and adapted to alternately engage said arm, a distributor switch driven in synchronism with said contact member, a voltage supply source having its positive terminal connected to said distributor switch, an electron discharge device having an anode, a control grid, screen grid and a cathode, a first resistance connected from a brush on said distributor to the arm of said contact member also to said screen grid, a second resistance connected from said screen grid to said pair of contacts and to the cathode of said electron discharge device, a transformer winding for supplying a tone frequency having one side connected to a control grid of an electron discharge device through a bias source, the other side of said transformer being connected to said cathode and to said pair of contacts, an output circuit coupled to the anode cathode circuit of said device, a receiver input at another location removed from said first mentioned location, an electron discharge device at said other location having at least an anode cathode and a grid, a connection from said receiver input through a limiting resistor to said last mentioned grid, a resistance connected in series with a source of potential and the anode of said last electron discharge device, and a distributor switch also at said other location and having a pair of spaced brushes, said distributor rotating in synchronism with said first mentioned distributor, a connection from the anode of said last mentioned electron discharge device to a segment on said last mentioned distributor adapted to alternately contact said brushes, a relay, means to connect said relay to the brushes of said distributor at said receiver location for receiving the transmitted marking impulses to thereby hold said relay in a position to which it was set during the previous elemental period.

3. A telegraph system in accordance with claim 2, characterized in that said relay comprises a push-pull electronic relay.

4. A telegraph system having means for transmitting marking and spacing signals in accordance with the message to be transmitted, and means in synchronism with said first mentioned means for transmitting at the beginning of the message an impulse which is of a duration shorter than the duration of either the marking or spacing signals during the occurrence of said signals.
